WELL SCREEN

Arthur L. Armentrout, Bakersfield, and Elwin B. Hall, Los Angeles, Calif., assignors, by direct and mesne assignments, to Security Engineering Co., Inc., Whittier, Calif., a corporation of California

Application July 5, 1935, Serial No. 29,990

1 Claim. (Cl. 166—5)

This invention relates to well apparatus and relates more particularly to a liner or screen for an oil well or gas well. A general object of the present invention is to provide a practical, effective liner or screen for a well.

When a productive stratum has been encountered or found in an oil well or gas well it is the usual practice to set a liner or screen in the productive zone to prevent the sanding up and caving in of the productive portion of the well. The usual or typical liners or screens are made up of lengths of steel pipe provided with perforations, perforated inserts and/or wrappings of wire to prevent the entrance of sand, gravel, etc., to the liner and the well. It has been found that the salt water, mineral acids, etc., often encountered in the wells corrode and quickly destroy the metal screen pipe and the wire wrappings, etc., necessitating the early replacement 10 of the liner or screen. After a relatively short period of use the sand and gravel of the formation tightly pack about a liner or screen due to the caving of the formation and the influx of the gas and oil. The packing of the sand and 15 gravel about the liner or screen usually makes it extremely difficult to remove the liner or screen for the purpose of replacement or for deepening the well and in many cases expensive fishing operations must be resorted to to 20 remove the metal liner or screen from the well.

Another object of the present invention is to provide a liner or screen for a well that does not require withdrawal from the well when it is desired to deepen the well or replace the liner.

Another object of the invention is to provide a liner or screen that is formed of frangible or friable material so that it may be easily broken and drilled up when it requires replacement or when it is desired to deepen the well.

Another object of the invention is to provide a liner or screen of the character mentioned that is formed of a material that is substantially unaffected by the salt water, acids and the like that may be present in the well.

Another object of the invention is to provide a frangible or friable liner or screen of the character mentioned that is effective in admitting the well fluids while excluding or screening out the sand, etc.

Another object of this invention is to provide the novel combination of a screen or liner and a means for locating or setting the same in a well that insures the safe easy positioning of the friable liner in the desired position in the well.

Another object of this invention is to provide a means or device for setting a liner or screen in a well that is operable to flush and wash the wall of the well bore as the liner is being set to remove mud, etc., from the wall of the well and thus permit the free flow or influx of the oil, 5 gas, etc.

Another object of this invention is to provide a frangible or friable liner or screen of the character mentioned that is capable of dependably withstanding the flow and pressure conditions to which it may be subjected when in use. The liner or screen of the present invention may be reinforced so that it may be handled and run 10 into the well without danger of breaking or failing and so that it is adapted to dependably withstand the conditions to which it may be subjected in the well bore.

A further object of this invention is to provide a well liner or screen of the character mentioned 20 that is simple and inexpensive of manufacture.

The various objects and features of our invention will be fully understood from the following detailed description of typical preferred forms and applications of the invention, throughout 25 which description reference is made to the accompanying drawings, in which:

Fig. 1 is a central longitudinal detailed sectional view of one form of the liner in position in the well bore with the carrying or setting string connected thereto. Fig. 2 is an enlarged transverse detailed sectional view taken as indicated by line 2—2 on Fig. 1. Fig. 3 is an enlarged fragmentary vertical detailed sectional view of a portion of a joint between two body sections, illustrating the 30 connection between the reinforcing wires. Fig. 4 is an enlarged fragmentary exterior view of the liner taken as indicated by line 4—4 on Fig. 1 illustrating one form of screen band. Fig. 5 is a view similar to Fig. 4 illustrating another form 35 of screen band. Fig. 6 is an enlarged fragmentary vertical detailed sectional view illustrating an insert arranged in an opening of the liner. Fig. 7 is a sectional view of the lower portion of a well bore illustrating the liner of the present invention entering the same, and showing the manner in which the fluid is discharged to wash the 40 wall of the bore. Fig. 8 is a view similar to Fig. 1 with the setting and flushing string removed and Fig. 9 is a central longitudinal detailed 45 sectional view of another form of the invention showing the setting and flushing element connected therewith and extending therethrough.

The form of the present invention illustrated in Figs. 1 to 8, inclusive, of the drawings, includes, 50

generally, a tubular friable body 10, a shoe 11 on the lower end of the body 10, and means 12 for positioning or setting the liner body 10 in the well and for flushing and washing the wall of the well bore B.

The liner or screen body 10 is an important feature of the present invention. The body 10 is an elongate tubular member or structure adapted to be run into the well to a position in the open productive portion of the well bore B. The length of the body 10 depends upon the extent of the productive stratum or zone of the well in which the liner is to be used. Accordingly, the body 10 is preferably sectional comprising as many sections 13 as may be needed. The body sections 13 are preferably connected by flush threaded connections 14 and are preferably of uniform internal and external diameter. A head section or cap 15 is threaded to the upper end of the uppermost body section 13. The cap 15 is tubular having a central longitudinal opening 16 which is of less diameter than the central longitudinal opening 17 of the body 10. The upper end 18 of the cap 15 is preferably tapered downwardly and inwardly for the purpose to be hereinafter described.

In accordance with the invention the body 10 is drillable or friable so that it may be readily drilled up by a drilling tool when it is desired to remove the liner or screen from the well. The body 10, that is the sections 13 and the cap 15, may be formed of cement, a composition of cementitious materials, bakelite, ceramic material, glass or any other material having the required strength and resistance to the action of the fluids in the well and that is drillable or capable of being broken up and drilled up by a well drilling tool. The body 10 of the form of the invention illustrated in Figs. 1 to 8, inclusive, of the drawings, is shown as formed of cement or the like, while the body of the liner illustrated in Fig. 9 is shown as formed of glass, it being understood that the body may be formed of any of the materials mentioned above or any equivalent materials. Where the well contains fluids destructive to cement and the like it is preferred to make the body 10 of bakelite or other material that is not affected by the fluids.

It may be preferred or desired to reinforce the drillable or friable liner body 10. In the particular case illustrated in the drawings longitudinally extending rods or wires 19 are molded or cast in the body sections 13 to form reinforcements. The end portions of the reinforcing wires 19 extend into recesses 20 in the adjacent or connected end portions of the body sections 13. The exposed end portions of the wires 19 of the connected sections may be twisted or linked together as shown at 21. The linked portions of the reinforcing wires 19 may be welded as at 22 or the linking or tying of the wires 19 may be dispensed with and the end portions of the wires may be welded together in any suitable manner. Following the connecting or welding of the wires 19 the recesses 20 may be filled with cement 23 or the like. The wires 19 extending longitudinally through the walls of the body sections 13 effectively reinforce the body sections and as the wires 19 of the several sections are tied or welded together they strengthen and reinforce the entire assembly.

The liner or screen body 10 is perforated, the sections 13 being provided with multiplicities of openings 24 in their walls. The openings 24 are

spaced longitudinally and circumferentially of the body sections 13 to admit fluid from the well bore B to the body opening 17. It is to be understood that the upper end portion of the body 10 which may extend into the well casing C may be imperforate or devoid of openings. In the particular structure shown in the drawings the openings 24 are round or cylindrical, it being understood that the openings may be of any desired configuration. It is preferred to provide the openings 24 with screens or screen means for preventing the entrance of gravel, sand, and the like into the body opening 17. The present invention broadly contemplates the employment of various forms of means for screening the openings 24. Where the character of the material of which the body sections 10 are formed permits the openings 24 may be of such size and shape that they do not require additional means for preventing the entrance of sand and gravel into the openings 17. In the drawings we have illustrated several typical means for screening the openings 24, it being understood that the invention in its broader aspect is not to be construed as limited to the particular screen means shown.

In Figs. 1, 2, 4, 5, 7 and 8 of the drawings the openings 24 are in circumferential series and bands 25 surround the body sections 13 and extend across the outer ends of the openings 24. The bands 25 are preferably embedded or countersunk in the exteriors of the body sections 13 and may be provided on the sections 13 when they are formed or cast. The bands 25 are rigid or fixed against movement and are preferably formed of hard material. The bands being in effect screens it is preferred that they be made of a hard wear resisting material. In practice any hard material such as screen parts of this nature are ordinarily made of can be used. In any particular case the conditions may determine the material used. Metal, glass and like hard materials are known in the art for this sort of use. Series of openings or slots 26 are provided in the bands 25 to communicate with the openings 24. The size or width of the slots 26 depends upon the conditions prevailing in the well. In Figs. 1, 2, 4, 7 and 8 of the drawings the slots 26 extend vertically while in Fig. 5 of the drawings the slots 26 extend horizontally it being understood that the fluid admitting slots 26 may be vertical, horizontal or inclined as desired. The slots 26 are proportioned to exclude or screen out the sand or gravel and admit oil, gas and other fluids into the openings 24 in the required volume. The bands 25 provided with the relatively narrow slots 26 effectively exclude the sand and gravel from the openings 24 and protect the body sections 13 against the excessive erosion or cutting away action of the fluids.

Fig. 6 of the drawings illustrates a form of the invention in which inserts 27 of hard material are threaded in the openings 24. The inserts 27 are preferably substantially flush with the internal and external surfaces of the body sections 13 and are fixed or immovable in the openings. Plurality of slots 28 are provided in the inserts 27 to pass or admit fluid into the openings 24 and the body opening 17 from the productive stratum. The openings 28 are preferably of inwardly increasing width so that their relatively narrow outer ends may effectively exclude the sand, while their wider inner portions may provide for the maximum flow of fluid into the body opening 17. It is to be understood that inserts of the character shown in Fig. 6 of the drawings

may be employed in connection with any forms of the present invention and may be used in substitution for or in addition to the bands 25 described above.

5 The shoe 11 is provided on the lower end of the body 10 to guide the body through the well and to support the body on the bottom of the well bore B. The shoe 11 also discharges fluid to clean the wall of the well bore B as will be 10 hereinafter described. The shoe 11 is frangible or friable and may be formed of the same material as the body 10. It may be preferred, however, to form the shoe 11 of somewhat harder material than the body 10. For example, it may 15 be preferred to form the shoe 11 of marble or the like. The shoe 11 is threaded or otherwise secured to the lower end of the lowermost body section 13. In the particular case illustrated in the drawings the shoe 11 has a threaded socket 20 30 in its upper end receiving a threaded pin 31 on the lower end of the lowermost body section 13. The lower end of the shoe 11 is imperforate or closed and is rounded or substantially spherical to effectively guide the liner body 10 through 25 the casing C and bore B.

The means 12 for positioning or setting the liner body 10 in the well, and for flushing and washing the wall of the bore B includes a string S of tubing or pipe adapted to carry or suspend 30 the liner body 10 for the purpose of running it into the well. The string S may be made up of a multiplicity of lengths of tubing or pipe in the well known manner. The lower parts or sections 32 of the string S extend longitudinally 35 through the opening 17 of the liner body 10. The lower end of the string S is removably connected with the shoe 11 which may be considered an element of the means 12 if desired. In the preferred construction illustrated the lower end of 40 the lowermost section 32 of the string S is threaded in a socket 33 in the shoe 11. The threads on the lower end of the section 32 and on the wall of the socket 33 are preferably left-hand threads so that they may be easily disengaged 45 by turning the string S without loosening the other threaded connections of the string. In the particular form of the invention being described the sections 32 of the string S extend through 50 the body opening 17 with considerable clearance so that they do not contact the wall of the opening 17.

The cap 15 may carry a ring 34 of rubber or the like to engage about the string S to form a shock absorber and guard. The threaded joints 55 or connections 35 between the sections 32 located within the opening 17 are internal joints or flush joints so that the portion of the string S which extends into the opening 17 does not present any shoulders which might interfere with the cap 15. The liner body 10 supported at its lower end on 60 the string S through the medium of the shoe 11 is not subjected to tensile strains as it is run into the well. The cement or material of which the body 10 is formed is capable of withstanding 65 considerable compression strain without failure and as the body 10 is only under the compression strain imposed by its own weight there is little or no danger of the body 10 breaking or failing when it is run into the well bore on the string S. Thus the body 10 supported from its lower end 70 on the string S when being run into the well and set is not liable to fail or break.

In accordance with the invention the means 12, together with the shoe 11 is adapted to discharge water or other suitable fluid outwardly against

the wall of the bore B to wash the same as the liner body 10 is being run through the bore and is being set. The invention provides a plurality of circumferentially spaced lateral discharge ports 36 in the shoe 11. A chamber 37 is provided in the lower end of the socket 33 and the ports 36 communicate with the chamber to discharge the fluid outwardly. Water or other suitable fluid is adapted to be passed or pumped through the string S to discharge from the ports 36 and wash 10 the wall of the bore B.

It is believed that the use and operation of the form of the invention illustrated in Figs. 1 to 8 of the drawings will be understood from the foregoing detailed description. The body 10 constructed and made up as described above, is provided with the shoe 11 and is run into the well bore on the string S which is connected with the shoe 11. The body 10 supported on the shoe 11 which in turn is connected with the lower end of the string 13 is not under tension as it is run into the well and, therefore, is not liable to fail or break. The lower end of the friable body 10 is rigidly connected with the string S by the shoe 11 while the upper end of the body bears or rests 25 on the string through the medium of the cap 15 and the ring 34. In being associated with the string S in this manner the body 10 does not move or vibrate relative to the string. The wires 19 effectively reinforce the body 10 and connect 30 its several sections 13 against unthreading or detachment one from the other.

When the string S has been lowered to a point where the liner or screen is entering or is about 35 to enter the open bore B water or other fluid is passed through the string S to discharge from the ports 36. This fluid or water is preferably under pressure so that it discharges from the ports 36 at a comparatively high velocity. The fluid or water discharging from the ports 36 as the liner 40 enters and passes through the bore B washes the wall of the bore free of mud and the like leaving the sands or formation clean so that the oil, gas and other fluid may freely flow into the well bore. This washing of the bore B is important as it 45 insures a greater and freer production of the oil and gas. When the shoe 11 reaches or rests on the bottom of the well bore the discharge of the fluid from the shoe 11 may be discontinued and the string S may be detached from the shoe 11. 50 The string S may be easily disconnected from the shoe 11 by rotating it to unthread the lower end of its lowermost section 32 from the socket 33. The string S is then removed from the well leaving the liner or screen in its operative position 55 in the bore B.

The oil, gas and other fluid from the sands or formation flows through the slots 26 or 28 and the openings 24 into the body opening 17 and is free to pass upwardly from the opening 17 into 60 the casing C. As described above, the bands 25 or the inserts 27 effectively exclude the sand and gravel from the liner opening 17 and allow the free entrance of the well fluids into the opening. When it becomes necessary or desirable to remove 65 the liner or screen for the purpose of replacing the same or for cleaning the well or for deepening the well a suitable drilling tool, preferably a rotary drilling tool, is run into the well and is operated to drill up the liner. The inclined upper end 18 of the cap 15 is adapted to guide the advancing part of the drill into the body opening 17. The body 10 and the shoe 11 being friable or frangible as described above are readily drilled 70 up and destroyed by the drill. The metal parts 75

that may be embodied in the liner or screen are small and quickly drilled up by the drill. The drill which is employed to drill up the liner may be employed to deepen the well if this is necessary or desired. As the liner of the present invention is formed principally of frangible or friable material it may be quickly drilled up by a drilling tool and, therefore, does not require removal from the well under any circumstances. As described above, the body 10 and the shoe 11 may be formed of material or materials that are substantially unaffected by the fluids in the well so that they are very long wearing.

Fig. 9 of the drawings illustrates an embodiment of the invention including a body 10^a formed of glass and a slightly modified form of means 12^a for setting or positioning the liner in the well and for flushing the well bore.

The body 10^a may be of the same shape and construction as the body 10 being an elongate tubular structure formed of a plurality of threadedly connected sections 13^a. As the body 10^a is formed of glass it may not be necessary to reinforce it although it may be reinforced with rods or wires if desired. The body 10^a is provided with a plurality of circumferentially and longitudinally spaced openings 24^a for admitting the oil, gas, etc., from the well bore into the central longitudinal openings 30. The openings 24^a may be 30 in the form of slots proportioned to exclude the sand or gravel without the addition or use of special strainers or screens. It is to be understood of course that screening means similar to those described above may be embodied in this 35 form of the invention if desired. A head section or cap 41 is provided on the upper end of the body 10^a. A shoe 11^a is provided on the lower end of the body 10^a. The shoe 11^a may be substantially identical with the shoe 11.

40 The means 12^a includes a string P of tubing or pipe and a tubular element 42 on the lower end of the string P extending longitudinally through the body 10^a. The tubular element 42 fits the body opening 40 rather closely or accurately and 45 in the event that it is made up of a plurality of sections its threaded connections are flush so that it does not present external shoulders. The element 42 extends longitudinally through the body 10^a from one end to the other and continues 50 upwardly through the cap 41. The element 42 may be connected with the string P by an adapter or reducer 43. The lower end of the element 42 is threaded in a socket 44 in the shoe 11^a. The threads on the element 42 and the wall of the 55 socket 44 are preferably lefthand threads so that the element may be disconnected from the shoe by rotation of the string P without loosening the

threaded connections in the string. A chamber 45 is provided in the shoe 11 at the lower end of the socket 44 and a plurality of lateral discharge ports 46 extend outwardly from the chamber for the discharge of fluid into the well bore.

The use and operation of the liner and setting means illustrated in Fig. 9 of the drawings are substantially the same as those of the previously described form of the invention. The liner is run into the well on the string P and positioned in the open portion of the well bore. The element 42 in closely or accurately fitting the body opening 40 effectively braces the body 10^a against any jars or blows to which it may be subjected and, therefore, prevents breakage of the body as it is being run into the well. As the liner enters the open portion of the well bore fluid under pressure is pumped through the string P to discharge from the ports 46 and wash the wall of the bore. The element 42 in closely fitting the body 20 opening 40 closes the inner ends of the openings 24^a and thus prevents the entrance of mud, sand, etc., into the liner body. When the liner has been set in the desired position the string P is rotated to disconnect the element 42 from the shoe 11^a 25 and the string with the element 42 is withdrawn from the well leaving the liner body 10 open to receive the oil, gas, etc. from the formation. The body 10^a in being formed of glass is substantially unaffected by the fluids in the well and is very 30 long wearing. When it is desired to replace the liner or deepen the well a drilling tool is run into the well and is operated to break up and drill up the friable body 10^a and the friable shoe 11^a leaving the well bore entirely clear. 35

Having described only typical preferred forms and applications of our invention, we do not wish to be limited or restricted to the specific details herein set forth, but wish to reserve to ourselves any variations or modifications that may appear 40 to those skilled in the art or fall within the scope of the following claim:

Having described our invention, we claim:

A liner of the character described for use in a well comprising a tubular body including a 45 plurality of drillable tubular sections having cooperatively engaged end portions coupling adjoining sections together end to end, there being fluid admitting openings in the walls of the sections, reinforcing members in the sections accessible at the ends of the sections when the sections are joined, the reinforcing members of the adjacent connected sections being engageable with each other to further couple the sections together.

ARTHUR L. ARMENTROUT.
ELWIN B. HALL.
